UNITED STATES PATENT OFFICE.

NATHANIEL W. VANDEGRIFT, OF BRIDGEPORT, CONNECTICUT, ASSIGNOR TO
FRANK ARMSTRONG, OF SAME PLACE.

WRENCH.

SPECIFICATION forming part of Letters Patent No. 298,043, dated May 6, 1884.

Application filed November 5, 1883. (No model.)

To all whom it may concern:

Be it known that I, NATHANIEL W. VANDEGRIFT, a citizen of the United States, residing at Bridgeport, county of Fairfield, and State of Connecticut, have invented new and useful Improvements in Wrenches, of which the following is a specification.

My invention relates to certain improvements in adjustable wrenches. It has for its object to provide a wrench simple and economic in construction, and adapted to be readily operated in cramped or close quarters, as well as in open and free spaces, and to be removed and replaced on the work without slackening the adjustment; and with these ends in view my invention consists in the peculiar construction and arrangement of parts, hereinafter fully described and specifically claimed.

In order that those skilled in the art to which my invention appertains may know how to make and use the same, I will proceed to describe its construction and operation, referring by letters to the accompanying drawings, in which—

Figure 1 is a side view of a wrench embodying my invention. Fig. 2 is a back view of the same, and Fig. 3 is a rear end view.

Similar letters indicate like parts in the several figures.

A represents the frame cast with cheeks or bearings *a* and with a longitudinal channel, in order that a handle, B, (preferably pipe,) may be secured at one end, and to admit of the passage of the adjusting-screw C of the sliding jaw D. Said frame is also provided with a transverse opening to receive the milled nut E, employed to operate the sliding jaw. The jaw F is secured pivotally between the cheeks or bearings *a* of the frame A by a bolt or pivot, *b*, and a spring, *c*, is interposed between the under side of the rear end or tail, G, of the jaw F and the upper surface of the frame, said spring operating to depress the front end of the jaw and hold it to its work. The sliding jaw D is secured by bolts or rivets *d* to a sliding yoke, H, which embraces the tail G of the jaw F, the height of the opening through said yoke being slightly in excess of the thickness of said tail, as indicated by parallel dotted lines, Fig. 1, and as clearly shown

at *e*, Fig. 3. The working-faces of the jaws D F, I have shown serrated, such configuration being most effective when used as a pipe-wrench; but it will be understood that they may be of any other suitable configuration, according to the work they may be designed for.

It will be observed that by reason of the pivotal connection between the tail of the jaw F and the frame A the former is capable of a vibratory movement equal to the extent of the space *e* between the yoke and the tail.

In using my improved wrench the jaws are placed loosely over the work, and the sliding jaw D is advanced by turning the nut E, the screw C being guided longitudinally by reason of the screw-stud I, projecting within a longitudinal groove in the lower side of said adjusting-screw C. The advancement of the jaw D is continued until the long lever-jaw F rises from its normal seat, as shown at Fig. 1, up into the space *e*, and against the under side of the yoke H, which limits the movement in such upward direction. During the upward movement of the jaw F, the spring *c* is compressed, so that its reactionary force is exerted to hold the jaw to its work, so that when power is applied to the handle B the forward end of the jaw F is drawn down and the work between the two jaws is tightly crimped until the jaw F, in its downward movement, reaches the lower seat, *e*, in the yoke H, which prevents any further crimping, and thus prevents the crushing of the work confined.

It will be seen that the grip of the jaws will be in proportion to the power applied to the handle; or, in other words, the work is clamped tightly between the jaws; and it will be seen that the raising of the handle B releases the grip of the jaws, and hence it is obvious that when the wrench is used in places where the operator is circumscribed in room, the handle may be raised and lowered like the handle of a pump or ratcheted drill, and the work will be accordingly released and regripped without slackening or altering the adjusting-screw C.

What I claim as new, and desire to secure by Letters Patent, is—

1. The frame A, provided with the handle B, screw C, and adjusting-nut E, and having the cheeks or bearings *a*, in combination with

a sliding jaw, D, secured to a movable yoke, H, and a rocking or lever jaw, F, having its tail G connected pivotally to the cheeks a of the frame, whereby, when the jaws are placed against the work, grip or release may be effected by the downward or upward movement, respectively, of the handle, as and for the purposes hereinbefore set forth.

2. In combination with the pivoted jaw F, sliding jaw D, frame A, and screw C, the yoke H, secured to the jaw D, and embracing the

jaw F, in a manner described, with a space, e, to permit vibratory movement of said jaw and protect the work from a crushing strain, substantially as hereinbefore set forth. 15

In testimony whereof I have hereunto set my hand in the presence of two subscribing witnesses.

NATHANIEL W. VANDEGRIFT.
